UNITED STATES PATENT OFFICE.

JOHN L. BISHOP, OF BEETOWN, WISCONSIN.

SLIDING DOOR.

Application filed February 14, 1923. Serial No. 619,025.

To all whom it may concern:

Be it known that I, JOHN L. BISHOP, a citizen of the United States, residing at Beetown, in the county of Grant and State of

5 Wisconsin, have invented certain new and useful Improvements in Sliding Doors, of which the following is a specification, reference being had to the accompanying drawings.

10 This invention relates to certain improvements in sliding doors and has relation more particularly to an inside door for a box car and it is an object of the invention to provide a door of this general character having 15 novel and improved means whereby the same may be effectively maintained in either closed or open position.

Another object of the invention is to provide a door of this general character having 20 novel and improved means whereby the same when in open position is effectively housed and wherein means is provided for access within the housing to clean out the same when the occasions of practice may require.

25 The invention consists in the details of construction and in the combination and arrangement of the several parts of my improved sliding door whereby certain important advantages are attained and the device rendered simpler, less expensive and otherwise more convenient and advantageous for use, as will be hereinafter more fully set forth.

30 The novel features of my invention will 35 hereinafter be definitely claimed.

In order that my invention may be the better understood, I will now proceed to describe the same with reference to the accompanying drawings, wherein:—

40 Figure 1 is a fragmentary sectional view taken through a box car with my improved sliding door in closed position;

Figure 2 is a sectional view taken substantially on the line 2—2 of Figure 1;

45 Figure 3 is a sectional view taken substantially on the line 3—3 of Figure 1;

Figure 4 is a fragmentary sectional view taken through a box car with the door in its open position and enclosed within the 50 housing therefor;

Figure 5 is a sectional view taken substantially on the line 5—5 of Figure 4;

Figure 6 is a view taken substantially on the line 6—6 of Figure 4.

55 As disclosed in the accompanying drawings, B denotes a box car of a conventional

type and which is provided with the entrance or door opening D. Associated with the opening D is an outside sliding door S of any ordinary or preferred type.

60 A side wall of the car B to one side of the opening D has associated therewith a housing H, the end thereof immediately adjacent to the door opening D being open but adapted to be closed by the swinging panel 65 or wall 1, the outer vertical marginal portion of said wall or panel 1 being hingedly connected as at 2 with the outer face of the housing H.

70 The top of the housing H is also open but adapted to be closed by the swinging top wall or panel 3, the outer marginal portion of said wall or panel 3 being hingedly connected as at 4 to the outer face of the housing H. The central portion of the top wall or panel 3 has hingedly connected therewith as at 5 a hasp 6 which coacts with an outstanding staple 7 carried by the adjacent side wall of the car whereby the top wall or panel 3 may be effectively locked in closed 75 position. The top wall or panel 3 serves to prevent access of grain or other matter within the housing H and by having said wall or panel 3 hingedly connected it can be readily adjusted into open position when it is desired to have access within the upper portion of said housing H as for the purposes 80 of repair.

85 Arranged within the housing H and extending lengthwise thereof and supported 90 by the brackets 8 is a track 9 upon which are slidably mounted the hangers 10 for the inside door A. The hangers 10 are positioned within the housing H when the door A is in either open or closed position and the housing H and the track 9 are of such length as to permit the door A to be completely contained within the housing H when the door A is in open position. When it is desired to move the door A into or out of 100 the housing H the wall or panel 1 is first swung into open position and after the desired adjustment of the door has been accomplished, the wall or panel 1 is returned to closed position and maintained in such 105 position by the sliding bolt 11 of a conventional type.

110 In order that the door A may have free sliding movement, the lower marginal portion thereof is slightly spaced from the bottom or floor of the car B and in order to close such space across the entrance or door

opening D, when the door A is in closed position, I provide the lower marginal portion of the door A, or more particularly that portion of the door which extends 5 across the opening D, with the swinging flap or strip 12, said strip being shown in a raised position in Figure 4 in order to facilitate the travel of the door A within the housing H.

- 10 The outer vertical marginal portion of the door A is provided with an open recess or notch 14 which, when the door is in closed position receives an outstanding staple 15 carried by the jamb 16 of the opening D remote 15 from the housing H. The outer vertical marginal portion of the door A carries a sliding bolt 17 of a conventional type which engages with said hasp 14 to maintain the door A in its closed position.
- 20 The outer portion of the door A or that portion which extends across the opening D when the door is in closed position, comprises an inwardly swinging section 18 which is hingedly connected as at 19 to the door A proper. When the section 18 is in its raised 25 position it is maintained in such position by the sliding bolt 20 of a conventional type carried by the hinged marginal portion of the section 18 and which is engageable with a keeper 21 carried by the adjacent portion of the door A proper.
- 30 The inner marginal portion of the panel or wall 1 is cut away as at 22 to compensate for the thickness of the door A and particularly when said door is in closed position.

The outer wall of the housing H is provided at its lower marginal portion with a swinging panel or flap 23 normally maintained in closed position in a conventional 40 manner by the sliding bolt 24 of any ordinary or preferred type. The panel or flap 23 provides means whereby access may be had within the lower portion of the housing H to sweep out therefrom grain or the like 45 which may accumulate therein.

In the present embodiment of my invention the door A is disclosed as a type for use in connection with grain but it is to be understood that the door may be otherwise 50 formed as the necessities of practice may prefer such as for use in connection with a stock car.

From the foregoing description it is thought to be obvious that a sliding door constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my 55

invention in practice except as hereinafter claimed.

I claim:—

1. In combination with a wall provided with an entrance opening, a housing associated with said wall at one side of and adjacent to the entrance opening, the end of the housing adjacent to the opening being open, a sliding door for said opening, said door being of a length materially in excess of the 75 width of the opening, an end portion of the door being arranged at all times within the housing, said portion of the door being provided with hangers at longitudinally spaced points, a trackway within the housing with 80 which the hangers engage for supporting the door in its entirety for sliding movement into either open or closed position with respect to the entrance opening, said door when closed being entirely confined within the 85 housing, the portion of the door extending across the entrance opening when the door is in closed position comprising a section adapted to swing in a direction away from the wall to open a portion of the entrance 90 opening when the door is in closed position, and means for holding said section against swinging movement.

2. In combination with a wall provided with an entrance opening, a housing associated with said wall at one side of and adjacent to the entrance opening, the end of the housing adjacent to the opening being open, a sliding door for said opening, said door being of a length materially in excess 100 of the width of the opening, an end portion of the door being arranged at all times within the housing, said portion of the door being provided with hangers at longitudinally spaced points, a trackway within the housing with 105 which the hangers engage for supporting the door in its entirety for sliding movement into either open or closed position with respect to the entrance opening, said door when closed being entirely confined within the housing, the portion of the door extending across the entrance opening when the door is in closed position comprising a section adapted to swing in a direction away from the wall to open a portion of the entrance 110 opening when the door is in closed position, and coacting means carried by the swinging section and the door proper for holding said swinging section in closed position.

3. In combination with a wall provided with an entrance opening, a housing associated with said wall at one side of and adjacent to the entrance opening, the end of the housing adjacent to the opening being open, 115 a sliding door for said opening, said door being of a length materially in excess of the width of the opening, an end portion of the door being arranged at all times within the housing, said portion of the door being pro- 120 130

vided with hangers at longitudinally spaced points, a trackway within the housing with which the hangers engage for supporting the door in its entirety for sliding movement into either open or closed position with respect to the entrance opening, said door when closed being entirely confined within the housing, the portion of the door extending across the entrance opening when the door is in closed position comprising a section adapted to swing in a direction away from the wall to open a portion of the entrance opening when the door is in closed position, means for holding said section against swinging movement, an outwardly swinging panel carried by the 15 housing, said panel when in one position closing the open end of the housing, and means for holding said panel in such position.

In testimony whereof I hereunto affix my 20 signature.

JOHN L. BISHOP.
